DESIGN FOR A FITTING CARRYING PIPE LINE CONTROL PLATE

Leland S. Hamer, Long Beach, Calif.

Application December 15, 1944, Serial No. 116,918

Term of patent 14 years

(Cl. D91—1)

To all whom it may concern:

Be it known that I, Leland S. Hamer, a citizen of the United States, residing in the city of Long Beach, county of Los Angeles, and State of California, have invented a new, original and ornamental Design for a Fitting Carrying Pipe Line Control Plate, of which the following is a specification, reference being had to the accompanying drawing, forming a part thereof.

Fig. 1 is a perspective view of a fitting carrying pipe line control plate showing my new design; Fig. 2 is a top plan view thereof; Fig. 3 is an

end elevational view taken from the front of Fig. 1; Fig. 4 is a side elevational view taken from the right of Fig. 3; and Fig. 5 is a view similar to Fig. 3 taken from the opposite end of Fig. 1. The ported tie bolt heads appearing in Figs. 1, 2, 3 and 4 are shown in a different rotative position in Fig. 1 than in the other figures.

I claim:

The ornamental design for a fitting carrying pipe line control plate, as shown and described.

LELAND S. HAMER.
